UNITED STATES PATENT OFFICE.

ROGERS D. McMAHON, OF CORAOPOLIS, PENNSYLVANIA.

ORNAMENTAL STRIP FOR BUMPERS.

Application filed October 27, 1926. Serial No. 144,466.

This invention relates to vehicle bumpers and more particularly to the application of an ornamental finish strip thereto.

One of the primary objects of the present invention is to provide an automobile bumper, that is pleasing in appearance, of few parts, and which will be simple and economical to manufacture and assemble.

A further object of the invention is to embody a sheet metal finish strip within a channel formed in the front or impact bumper bar, which arrangement in addition to improving the physical appearance, lessens the possibility of damage to the finish strip and permits the use of a comparatively light gage material.

Other incidental objects will appear from the following specification and the accompanying drawing, illustrating a preferred, but not necessarily the only form of the invention, wherein

Figure 1 is a top plan view of a conventional bumper attached at the front of an automobile, indicated in dotted lines;

Figure 2 is a front elevation of the bumper shown in Figure 1 with the present invention applied thereto;

Figure 3 is a vertical sectional view taken on a central line intermediate the ends of the bumper;

Figure 4 is a vertical section thru a single impact bar showing a modified construction; and

Figure 5 is a perspective view of a common form of quarter bumper embodying the present invention.

Referring to the drawing, the bumper, which may be of any desired construction, is here shown of the double bar type wherein, a pair of spaced front or impact bars 1 and 2 are supported by a single rear bar 3, positioned in a plane intermediate the impact bars. Hinge bolts 4 and 5 pass thru eyes formed at the respective outer extremities of the bars and clamp plates 6 and 6' at the center, fasten the three bars to each other. The bar 3 extending rearwardly, has a pair of brackets 7-7, for bolting the bumper to the longitudinal chassis frame members.

In the present instance, the spring steel impact bars, which are usually black enameled, are each formed with beaded edges providing an intermediate channel. To offset the dark color of the bumper bar, it is proposed to position within the before mentioned intermediate channel, a brighter col-

ored finish strip 9, preferably consisting of a rust proof sheet of light gage metal. For instance, a very pleasing contrast is had by employing a highly polished nickel plated finish strip. This inlaid strip may be held within the channel and between the longitudinal edge beads in any suitable manner, such as by bolts or rivets 10. The channel is made sufficiently deep that the beaded edges project beyond the face of the insert strip. It will be seen, therefore, that upon striking an object, the impact is received by the forwardly projecting beads of the bar, rather than by the finish strip, and the finish strip is thus protected from injury. For this reason, heavy gage stock is unnecessary, and the finish strip may be made of exceptionally light weight material.

In Figure 5, the quarter bumper, used quite generally at the rear of automobiles, consists of frame brackets 11 and 12, supporting by means of hinge bolts, the impact bars 13, having a finish strip 14, secured between the forwardly projecting beads as before described.

In order to prevent metallic contact between the finish plate and impact bar, a strip of cushioning material 15, such as cloth fabric or rubber, may be placed therebetween, as shown in Figure 4. Rattle of the parts and unnecessary noises are thus effectually rendered impossible.

While the parts and arrangement have been described more or less specifically, it is to be understood that such modifications may be made as come within the scope of the appended claims.

Having described my invention, I claim:

1. An automobile bumper having an insert within an indentation in one of the members thereof to impart a finish thereto, the front face of such insert being spaced inwardly from the front face of the bumper member.

2. An automobile bumper including an impact member having a channel therein and a finishing insert inlaid wholly within said channel, with its front face lying behind the forward face of the impact member.

3. An automobile bumper including an impact member, a sheet metal finish strip secured to said member, and a protective portion of said member projecting forwardly beyond the face of said sheet metal finishing strip.

4. The combination of an automobile bumper bar, having marginal beaded edges and a sheet metal finish strip secured to said bar intermediate said beaded edges, the face of said finish strip lying behind the forward faces of said beaded edges.
5. The combination of a bumper bar and a finish strip therefor, said bumper bar being provided with a pair of protective beads one on each side of and projecting beyond 10 said strip.
6. The combination of a bumper bar having a pair of longitudinal beads extending throughout its length, and a finish strip carried by said bar the face of which lies behind the forward face of said beads so as 15 to be protected by said beads.
7. The combination of a bumper bar having a channel therein, a sheet metal inlay 20 within said channel, and cushioning material disposed between said inlay and bumper bar to prevent rattle.
8. The combination of a bumper bar, a sheet metal finish strip secured thereto, and 25 a strip of cushioning material interposed between said bar and sheet metal finish strip preventing their contact to obviate rattle.
9. A vehicle bumper including a bar member having a portion thereof depressed 30 medially throughout its longitudinal extent

and a finish strip inlaid in the depression and being of relatively less thickness than the depth of said depression.

10. A vehicle bumper including a bar member, a finish strip carried thereby throughout the central portion thereof, the ends of the finish strip being spaced from the ends of the bar member, and a part of 35 said bar member projecting forwardly beyond the face of said finish strip.

11. A vehicle bumper including an impact member having a forwardly projecting beaded edge, a finish strip having a thickness less than that of said beaded edge and means to secure the said finish strip against 45 the forward face of the impact member, at points spaced from the respective ends of the impact member.

12. A vehicle bumper including an impact bar having a channel formed in the 50 forward face thereof, a finish strip of relatively less thickness than the depth of said channel located within said channel throughout the central portion of the bar to impart a finish thereto and attachment 55 means connecting the end portions of the strip to said bar at points spaced from the ends of the bar.

In testimony whereof I affix my signature.

ROGERS D. McMAHON.
